UNITED STATES PATENT OFFICE

CLYDE H. HORNER, OF PALMYRA, NEW JERSEY

DESIGN FOR A POWDER BOX

Application filed June 11, 1932. Serial No. 44,057. Term of patent 14 years.

To all whom it may concern:

Be it known that I, CLYDE H. HORNER, a citizen of the United States, and a resident of Palmyra, county of Burlington, State of New Jersey, have invented a new, original, and ornamental Design for a Powder Box, of which the following is a specification, reference being had to the accompanying drawing, forming a part thereof.

Fig. 1 represents a perspective of a box showing my new design; and Fig. 2 represents a section on line 2—2 of Fig. 1.

The opposite side is the same as the side shown in Fig. 1 of the drawing.

I claim:

The ornamental design for a powder box substantially as shown and described.

CLYDE H. HORNER.
